(57) **CLAIM**

The ornamental design for a display screen with animated graphical user interface, as shown and described.

DESCRIPTION

The file of this patent contains at least one drawing/photograph executed in color. Copies of this patent with color drawing(s)/photograph(s) will be provided by the Office upon request and payment of the necessary fee.

FIG. 1. is a front view of a first image of a display screen with animated graphical user interface showing a first embodiment of our new design;

FIG. 2. is a front view of a second image thereof;

FIG. 3. is a front view of a third image thereof;

FIG. 4. is a front view of a fourth image thereof;

FIG. 5. is a front view of a fifth image thereof;
FIG. 6. is a front view of a first image of display screen with a display screen with animated graphical user interface showing a second embodiment of our new design;

FIG. 7. is a front view of a second image thereof;

FIG. 8. is a front view of a third image thereof;

FIG. 9. is a front view of a fourth image thereof;

FIG. 10. is a front view of a fifth image thereof; and,

FIG. 11. is a front view of a sixth image thereof.

The appearance of the animated graphical user interface sequentially transitions between the images shown in FIGS. 1-5 and FIGS. 6-11. The process or period in which one image transitions to another image forms no part of the claimed design.

The outer peripheral broken lines represent a display screen or portion thereof and form no part of the claimed design. All other broken lines show portions of the graphical user interface and form no part of the claimed design.
